UNITED STATES PATENT OFFICE.

FRED W. WOLF, OF CHICAGO, ILLINOIS, ASSIGNOR, BY MESNE ASSIGNMENTS, TO THE ISKO COMPANY, OF CHICAGO, ILLINOIS, A CORPORATION OF DELAWARE.

PROCESS OF AND APPARATUS FOR REFRIGERATION.

1,291,334.

Specification of Letters Patent.

Patented Jan. 14, 1919.

Application filed April 8, 1918. Serial No. 89,770.

To all whom it may concern:

Be it known that I, FRED W. WOLF, a citizen of the United States, and a resident of Chicago, in the county of Cook and State of Illinois, have invented certain new and useful Improvements in Processes of and Apparatus for Refrigeration, and I do hereby declare that the following is a full, clear, and exact description thereof, reference being had to the accompanying drawings, and to the letters of reference marked thereon, which form a part of this specification.

This invention relates to an improved method of refrigeration and to an apparatus for carrying out said method and consists of the matters hereinafter described and more particularly pointed out in the appended claims.

The improved method is carried on in an apparatus of the compression type as distinguished from absorption systems and includes the usual compressor, a condenser, an expansion chamber and a reducing valve connecting the condenser with the expansion chamber. The improved method and apparatus are primarily intended for small units capable of use for domestic purposes and the object of the invention is to obviate the essential defects and disadvantages to be found in all compression systems as manufactured for refrigeration on a large scale or for the manufacture of ice for commercial purposes.

One disadvantage which is found in the compression system results from the leakage at the stuffing box in the compressor which is the one opening connecting the interior of the refrigerating apparatus with the outside air. If the apparatus is designed to run in pressure, a leak in the stuffing box results in a gradual loss of the refrigerant. If the machine is designed to run in vacuum, there is a leakage of air and of the moisture carried thereby into the apparatus through the stuffing box, with a resulting loss of the efficiency of the apparatus. These disadvantages are not of serious moment in large systems when an engineer is employed to look after the apparatus and attend to the stuffing box, but in a small, automatically controlled apparatus, a tendency to leak in the stuffing box is prohibitive of its use.

Another disadvantage of any refrigerating apparatus when applying it to domestic use is the necessity for cooling water to cool the condenser. There is not only the expense involved but also the clumsiness of the apparatus required for cooling, the difficulty in the control of the cooling water and of its final disposal.

My new refrigeration system and process are designed to do away with both of these difficulties, dispensing with the necessity for the use of cooling water on the one hand and preventing either an inward or outward flow through the stuffing box on the other hand.

In carrying out my invention I make use of an expansion valve which is controlled by the pressure of the atmosphere, thus maintaining the low pressure side of the system at a pressure substantially equal to that of the atmosphere no matter at what altitude the system is used nor how said pressure varies under varying climatic or barometric conditions. Since the pressure in the stuffing box is the same as that of the atmosphere, there is no tendency either for the outside air to flow through the stuffing box into the system or for the refrigerant to escape through the stuffing box into the outer air. Such an arrangement also has the added advantage that no adjustment of the valve is necessary and the objections due to the use of springs, weights or like adjusting devices in the apparatus is entirely done away with.

In addition I select a refrigerant which boils at atmospheric pressure at a sufficiently low degree below the freezing point to produce the temperature required in the ordinary domestic refrigerator at atmospheric pressure. A refrigerant boiling at about 14 to 15 degrees above zero F. at the pressure of atmosphere at sea level gives the best results. I have found that a most satisfactory and in fact the preferred refrigerant for the purpose is sulfur dioxide which boils at atmospheric pressure at 14° Fahrenheit.

Since the expansion valve is controlled by atmospheric pressure, the pressure in the condenser and its corresponding temperature are immaterial.

In the accompanying drawings, I have illustrated diagrammatically an apparatus

embodying my improved system by means of which the improved process may be carried out.

In the drawings:

5 Figure 1 illustrates a diagrammatic view of a refrigerating apparatus designed to carry out my improved process.

Fig. 2 illustrates a transverse vertical section on an enlarged scale through the 10 compressor forming a part of the apparatus.

Fig. 3 illustrates a vertical section through the valve controlling the flow of refrigerant from the condenser coil to the expansion coil, such valve being generally termed an 15 expansion valve.

Referring now to the drawing, 5 indicates a compressor having a driven pulley 6, adapted for the operation thereof. Said pulley is operatively connected by means of 20 one or more belts 7, to the driving pulley of a motor, 8. The driven pulley 6, is made heavy so as to act also as a fly wheel and the spokes thereof are preferably constructed to form fan like, spiral blades which act to 25 produce a draft in the vicinity of the compressor and to effect a continual change of atmosphere in and about the apparatus.

10 indicates the condenser coil which, in this instance, is made of tubing having a 30 comparatively small cross section and a comparatively thin wall. The inlet end, 10^a, of said coil is connected to the cylinder head 9, of the compressor in such manner as to receive the compressed refrigerant therefrom.

35 The outlet end, 10^b, of said coil is connected to the inlet end 11^a, of an expansion coil 11 by means of an expansion valve 12, which valve controls and regulates the amount of refrigerant admitted to said expansion coil.

40 The outlet end, 11^b, of said expansion coil is connected to the crank case of the compressor.

The compressor 5, comprises a crank case 13, to which is attached the cylinder, 14, 45 having the head 9, before mentioned. The crank case 13, has provided in one wall a blind or closed bearing 15, for one end of a crank shaft 16. The other end of said crank shaft has bearing in and projects through a 50 removable plate, which forms a wall 15^a, of the crank case and a stuffing box 17, of familiar construction is provided about the shaft bearing.

55 16^a indicates a crank arm and 18 a connecting rod, which is attached to a wrist pin 19, of a piston 20, adapted for reciprocating movement in the cylinder 14. In the piston is provided a spring-controlled inlet valve, 21, of familiar construction.

60 At the upper end of the cylinder 14, is formed a valve seat 22, and 23 indicates a spring-controlled valve plug of a diameter substantially equal to that of the cylinder which coacts with said seat and controls the 65 outlet of the compressed refrigerant from

the cylinder. 24 indicates a coiled spring, interposed between said valve and cylinder head 9.

The operation of said compressor is as follows: The crank case into which the outlet end, 11^b, of the expansion coil, 11, discharges, is filled, like the expansion coil, with expanded refrigerant at substantially atmospheric pressure. As the pressure in the crank case is higher than that within 70 the cylinder at the end of the down stroke of the piston, said pressure will cause the inlet valve 21, in the piston to open and the refrigerant will pass from the crank case into the cylinder. Upon the equalization of the 75 pressure which will occur just as the piston starts on its upward movement, said valve will close. Further upward movement of the piston will compress the expanded gas between the outlet valve 23 and the top of 80 the piston until the pressure therein is great enough to lift the outlet or discharge valve 23, against the combined action of the spring, 24, and the back pressure from the condenser coil. After the compressed gas 85 has been forced into the condenser coil, the discharge or outlet valve, 23, will again be seated. The hot, compressed gas delivered to the condenser coil is cooled and liquefied and delivered to the expansion valve 12, as 90 before described.

The expansion valve 12, as illustrated in the drawings, comprises a circular chambered plate 25, and a flat ring 26, which coincide at their peripheral edges. Said 100 plate and ring are attached together by means of screws, 27, and clamped between them is a disk or diaphragm 28, of thin flexible metal, a packing ring 29, being interposed between the marginal part of the diaphragm 28, and the plate 25, to insure a gas-tight connection between them.

The bottom of the plate 25, is concave and forms a shallow chamber 25^a, above the diaphragm. On the top of said plate is formed 110 a boss, 30, having a vertically extending passage 30^a, which is located concentrically with respect to the diaphragm 28, and which is adapted to receive the outlet end 10^b, of the condenser coil and constitutes the inlet to the 115 said expansion valve. 31 indicates the lower end of said passage which opens into the chamber 25^a, above the diaphragm. This chamber 25^a is normally closed off from the inlet end of said passage by means of a valve 120 32, having a head 33, adapted to close on an annular seat 34, formed in said passage.

The valve 32, has a stem 35, which is threaded through the diaphragm 28, and through relatively flat nuts 36-37, placed 125 on opposite sides of diaphragm, to rigidly connect the valve stem thereto. A lead washer 38, is preferably interposed between the bottom surface of the diaphragm and the nut 37, to prevent leakage in the con- 130

nnection between the valve stem and diaphragm.

In the boss 30, is formed a transverse passage 40, which constitutes the outlet of the 5 expansion valve and into which the inlet end 11^a of the expansion coil 11 is threaded. This passage is connected by means of a passage, 41, with the chamber 25^a above the diaphragm.

10 Condenser pressure will, of course, always maintain on the head 33, of the valve 32. The pressure in the expansion coil will be exerted on the top of the diaphragm, 28, while atmospheric pressure will maintain against 15 the bottom side of said diaphragm. Thus the operation of the diaphragm will depend upon the differential of pressure between the atmosphere and the pressure in the expansion coil. The atmospheric pressure 20 being constant, naturally the opening and closing of the valve will depend upon the variation of the pressure in the expansion coil. The large difference in area between that of the valve head, 33, and the top surface 25 of the diaphragm, 28, which is influenced by pressure in the expansion coil, will thus make the valve very sensitive to every slight variation in the pressure of the expansion coil upon one side or the other of 30 a certain pressure.

The expansion valve as illustrated herein is designed more particularly for use in connection with a refrigerating apparatus in which SO₂ is used as the refrigerant. 35 This for the reason that in the case of SO₂ a temperature of about 26° F. in the chamber in which the expansion coil is located corresponds to about 15° F. of temperature in the expansion coil itself and this temperature 40 corresponds to substantially atmospheric pressure in the expansion coil. Thus the pressure of the atmosphere on the bottom of the diaphragm may be made use of as the constant pressure in producing a 45 differential pressure on the diaphragm, thus doing away with springs, weights and similar devices, which while intended to be constant, are for various reasons not constant in their action and require adjustment.

50 While in the above I have referred to SO₂ as the refrigerant, it will be understood that the apparatus is equally capable of use to the same advantage with other refrigerants, it being simply necessary in the case of the 55 use of such refrigerant to so design the apparatus that it will operate to produce the required temperature in the compartment in which the expansion coil is located with approximately zero pounds gage or atmospheric pressure in the expansion coils.

From what has been said, it will be manifest that in the process carried on in the

apparatus as described, the refrigerant fluid, sulfur dioxid (SO₂) is compressed in the compressor in the usual manner. From the 65 condenser the fluid is admitted to the expansion coil by the expansion valve, which operates at approximately zero pounds gage pressure or atmospheric pressure, so that the low side of the system is maintained substantially at atmospheric or zero pounds gage pressure while the apparatus is in operation. Thus the refrigerant returned to the compressor, being at atmospheric pressure, will not tend to leak out through stuffing boxes provided in connection with the moving parts thereof, nor will the outside air tend to leak in. The operation of this apparatus and the process are entirely independent of the pressure in the high side 80 of the system, that is in the condenser. Thus, air alone with a suitable condenser coil for producing sufficient radiation, may be conveniently used for cooling the refrigerant.

I claim as my invention:

1. A process of refrigeration consisting in compressing a refrigerant, cooling the compressed refrigerant, expanding the cooled refrigerant into an expansion chamber and maintaining the refrigerant within said chamber at substantially atmospheric pressure for the purpose set forth.

2. A process of refrigeration consisting in compressing sulfur dioxid, cooling the compressed fluid, expanding the cooled fluid 95 into an expansion chamber, and maintaining the fluid within said chamber at substantially atmospheric pressure for the purpose set forth.

3. A process of refrigeration consisting in compressing a refrigerant, cooling the compressed refrigerant, expanding the cooled refrigerant into a chamber when the pressure therein falls below substantially atmospheric pressure and returning the expanded 105 refrigerant to be recompressed.

4. In a refrigerating apparatus having means to compress a refrigerant, means to cool the compressed refrigerant, and an expansion chamber all connected to form a 110 closed circuit for the refrigerant; the improvement comprising means to expand the cooled compressed refrigerant into said chamber when the pressure therein falls below substantially atmospheric pressure for 115 the purpose described.

In testimony, that I, claim the foregoing as my invention I affix my signature in the presence of two witnesses, this 21st day of March A. D. 1916.
